United States Patent Office.

CYRUS ROBERTS AND JOHN A. THROP, OF THREE RIVERS, MICHIGAN.

Letters Patent No. 99,951, dated February 15, 1870.

IMPROVEMENT IN HORSE-POWERS.

The Schedule referred to in these Letters Patent and making part of the same

To all whom it may concern:

Be it known that we, CYRUS ROBERTS and JOHN A. THROP, both of Three Rivers, in the county of St. Josephs, and State of Michigan, have invented certain new and useful Improvements in Horse-Powers, of which the following is a full, clear, and exact description.

The invention hereinafter claimed relates more especially to that class of machines known as mounted powers, and constitutes improvements on the machines shown in sundry Letters Patent of the United States heretofore granted to us, and respectively dated December 8, 1868, July 6, 1869, and July 13, 1869.

The first part of our invention relates to the staking or bracing of the power.

Its object is to prevent the yielding, working, or tipping of the machine while in operation; and the improvement consists—

First, in combining with the frame rigid thrust-braces, secured to its front and rear ends, on opposite sides of and crossing the frame.

Second, in combining rigid thrust-braces projecting on opposite sides and ends of the frame with flexible tension-braces, each attached at one end to the outer end of one rigid brace, and at its other end to the inner end of the opposite rigid brace.

Third, in combining reversible thrust-braces with adjustable flexible tension-braces, so constructed as to pass either above or below the main frame.

Fourth, in combining the rear rigid thrust-brace with a removable straining-rod connecting the ends of the side timbers of the frame, to equalize the strain thereon.

Fifth, in combining the frame, rigid thrust-braces, flexible tension-braces, and straining-rods, substantially as hereinafter shown.

The object of the next part of our invention is to apply the power from either end of the frame; and our improvement consists—

Sixth, in mounting the entire working mechanism in a metallic gear-frame, made reversible in its bearings.

The next part of our invention relates to the driving gearing; and our improvement consists—

Seventh, in mounting the inner end of the line-shaft in swiveling bearings adjustable vertically in their stirrup, to enable the shaft to work at different angles.

Eighth, in mounting the outer end of the line-shaft in an adjustable stirrup, to adjust that end in accordance with the adjustment of the other end.

Ninth, in combining a line-shaft mounted at one end in swiveling bearings in a stirrup on the bed-plate, and in an adjustable banger on the opposite end of the bed-plate.

Tenth, in so combining the line-shaft and tumbling-rod by a jaw and roller connection that the tumbling-rod may be turned up at right angles to the line-shaft for transportation.

Eleventh, in combining a jointed tumbling-rod with a removable straining-rod extending across the frame, which rod holds up the line-shaft when moving from place to place.

Twelfth, in combining vertically-vibrating bearing rollers for holding down the main gear-wheel with adjusting screws working through slotted brackets on the inner edge of the upper fixed ring bed-plate.

Thirteenth, in combining with the frame pivoted slotted intersecting standards, to carry the sweeps and braces when moving from place to place, but capable of being lowered upon the frame, out of the way of the sweeps when at work.

The accompanying drawings show all our improvements embodied in one machine; some of them, however, obviously may be used without the others, or adapted to machines differing somewhat in construction from that herein shown.

Figure 1 is a plan or top view of our improved machine, showing the tension-braces passing over the frame and the tumbling-rod extending behind the machine.

Figure 2, a similar view of a portion of the same, showing the tension-braces attached underneath the frame and the tumbling-rod in front.

Figure 3, a vertical longitudinal section at the line xx of fig. 1.

Figure 4, a view in perspective of the bed-plate.

Figure 5, a similar view of a portion of the same, showing the details of one of the bearing rollers.

Figure 6, a view in elevation of the stirrup and swiveling bearing of the front end of the line-shaft.

Figure 7, a view of the stirrup supporting the center of the line-shaft.

Figure 8, a front view of the supporting-rack.

A stout main frame, composed of longitudinal side timbers $A A^1$, converging slightly from rear to front, and connected by cross-bars $A^2 A^3$, is mounted on four wheels, $B B^1 B^2 B^3$.

The hind wheels are mounted on an axle fast to the frame, but the axle of the front wheels $B^2 B^3$ is pivoted on a king-bolt, b , to enable the machine to turn more readily. The narrowing of the frame in front leaves more room for the wheels to turn on the king-bolt.

Rigid thrust-braces $C C'$ are inserted into sockets c , respectively situated on the inner sides of the side timbers $A A^1$, near their front and rear ends, or otherwise securely connected with the beams. These braces, it will be observed, extend across the frame and project on the opposite sides thereof, and are staked to

the ground in the usual well-known way. This mode of bracing the frame enables us to use longer braces, and to arrange them at a less acute angle to the ground than the plans previously patented by us, thus obviating the tendency of the power to rise under the strain of the horses.

These braces thus arranged would work effectively without other bracing, but in order to secure the highest degree of efficiency and to relieve the main frame from strain, we prefer to combine with the thrust-braces above described flexible tension-braces D D', composed of jointed rods or chains, and attached at one end to the outer end of one thrust-brace, and at the other end to the inner end of the other thrust-brace. The strain of the tension-braces is thus thrown mainly on the stakes and on the thrust-braces, instead of acting directly on the main frame.

In this instance, rings d on the tension-braces slip loosely over the rounded ends of the thrust-braces, and are adjusted thereon by a series of holes in the thrust-brace, into any one of which a pin, e², may be inserted.

The other ends of the tension-brace hook into eyes d' on the thrust-braces.

It is obvious that the connection between the thrust and tension-braces may be formed in other well-known ways. In fig. 1 the tension-braces are shown as passing over the frame timbers, which mode we prefer, as the strain on the timbers aids in holding the frame down to the ground. Sometimes, however, other arrangements may be desirable, as, for instance, when working on hill-sides. To meet this contingency, the thrust-braces, one or both, may be turned in their sockets until their hooks d are brought underneath, and the tension-braces attached underneath the frame, as in fig. 1.

It is obvious that by using chains for the tension-braces, either or both of them might be passed under and hooked to the thrust-braces without turning the latter, and that the turning of these braces might be amended by placing hooks or loops on two of their sides.

The tension-braces are always kept taut by the adjusting pins heretofore described. We prefer that the braces should never touch the wheels, but that the latter should at all times be free to move. Should the wheels sink, as they sometimes do in soft soil, even to the hubs, the thrust-braces will sustain two corners of the frame, while the pull of the team will tend to lift the other two corners.

We insert a straining-rod, E, in open slots e, in the rear ends of side timbers, and tighten it up by a nut and screw or other well-known means. This straining-rod serves to brace the frame and to distribute the strain of the thrust-brace C between the two sides of the frame. It is made removable in order that the tumbling-rod, when turned up for transportation, may be held up by the straining-rod, as herein-after explained. The slots e might be closed and the rod E drawn through endwise, but this plan is not so convenient as the one shown.

In order to carry out the next part of our invention, we cast a bed-plate, F, of the form shown in the drawings, in one piece.

A fixed ring or yoke, F', rests upon pillars f on the bed-plate.

A bevel wheel, G, is mounted on a spindle, g, supported by a bridge on the bed-plate.

The gearing of our power is shown and described in our former patents, hereinbefore referred to, and is not therefore shown or described in detail here.

The line-shaft H at its inner end turns in a pipe box, h, oscillating on trunnions having their bearings in lining-plates h' adjustable vertically in the stirrup H' on the bed-plate by means of slots and set-screws

h². This end of the line-shaft can thus be adjusted relatively to the bevel wheel G.

A bevel pinion, g', mounted on the line-shaft, gears into the bevel wheel G, and runs in an oil cup, h³, bolted to the stirrup, thus economizing oil.

The outer end of the line-shaft runs in a box, i, suspended from a hanger, I, depending from the bed-plate.

The spindle i' of the box i passes through flanges on the hanger.

A collar, i², resting on the upper bracket, is pierced with holes at different heights. A pin inserted in any one of these holes regulates the height of the box and consequently the angle of the inclination of the line-shaft to the ground:

The bed-plate F, it will be observed, rests upon the side timbers A A', to which it is bolted by screws a. By simply detaching the bed-plate from the frame and turning it half way round the line-shaft I may be made to project in front instead of in rear of the frame.

The line-shaft H carries at its outer end trunnions, to which a jaw, j, is fixed. The tumbling-rod J is likewise pivoted to the jaw at right angles to the trunnions.

The jaw, it will be observed, is cut away at the back so as to permit it to be turned up at right angles to the line-shaft. When thus turned up it may be held up by a rod passed through the frame, or may rest against the removable straining-rod E, which must of course be removed before the tumbling-rod is turned up.

We are aware that swiveled tumbling-rods are old, but we are not aware of a tumbling-rod being constructed with a jaw and roller joint which allows the rod to turn up at right angles to the shaft.

In order to prevent the bevel wheel from rising out of contact with its gears, we mount a bearing roller, K, on an elbow lever, k, pivoted to vibrate vertically in the bed-plate.

The free end of the elbow lever plays freely in a vertical slot, l, in a bracket, L, on the yoke F'.

A set-screw, l', passes down through the bracket and serves to regulate the pressure of the bearing-roller on the bevel wheel.

This device is an improvement on that shown in our patent of December 8, 1868, and secures better work, as the guide-plate prevents the lateral deflection of the roller.

A roller, k, similar to that already described, is arranged on the bed-plate at right angles to the line-shaft, for a purpose fully described in our patent aforesaid.

When moving from place to place the sweeps and braces are carried on a frame or horse, formed by pivoting two slotted timbers, M, to the bolsters or frame, arranging them to cross each other, and connecting them by a set-screw, m, at their point of intersection. When working, these pieces are lowered upon the frame, out of the way of the sweeps. The machine is drawn by a tongue in the usual way.

In operation the sweeps are applied to the power in the usual way. The braces are applied as in fig. 1 or 2 and staked down to the ground, as shown. No fastening of the wheels is required. The horses move in the direction shown by the arrow in fig. 1. The tension-braces counteract any tendency to rise of the corners, at which the thrust-braces touch the frame, while the strain of the team depresses the other corners. The operation of the other parts of the mechanism needs no description here, being well known to all skillful builders of horse-powers.

We do not herein broadly claim bracing a horse-power, or the combination of rigid and flexible braces, neither do we claim the bed-plate or gearing.

We claim as our invention—

1. The combination with the frame of the rigid thrust-braces secured to its front and rear ends, on opposite sides of and crossing the frame in the manner described.
2. The combination of rigid thrust-braces on opposite sides and ends of the frame, with flexible tension-braces, each extending from one rigid brace to the other, substantially as set forth.
3. The combination of thrust-braces with tension-braces, arranged to pass either above or below the frame, as set forth.
4. The combination of the rear thrust-brace with the straining-rod, these parts being constructed to operate as set forth.
5. The combination of the frame, thrust-braces, tension-braces, and straining-rod, all these parts being constructed to operate substantially as set forth.
6. The combination with the main frame of the reversible bed-plate, these parts being constructed to operate substantially as hereinbefore set forth.
7. The combination of the stirrup H, the adjustable swivel bearings, and the line-shaft, all these parts being constructed to operate as set forth.
8. The combination of the bed-plate, adjustable stirrup I, and line-shaft, all these parts being constructed to operate as set forth.
9. The combination of the bed-plate, line-shaft, the swiveled bearing in the stirrup H', and the adjustable stirrup I on the opposite end of the bed-plate, all these parts being constructed to operate as set forth.
10. The combination of the line-shaft and tumbling rod by the jaw and roller joint, constructed as described, to permit the rod to be turned at right angles to the shaft.
11. The combination of the jointed tumbling-rod and removable straining-rod, these parts being constructed to operate as set forth.
12. The combination of the vibrating bearing-roller, its adjusting screw, and the slotted bracket on the upper ring of the bed-plate, all these parts being constructed to operate as set forth.
13. The combination with the frame of pivoted slotted intersecting supporting-standards, constructed to operate as set forth.
14. The combination of the line-shaft, the journal-box supporting its end, the stirrup H', and the oil cup, all these parts being arranged as set forth for joint operation.

In testimony whereof, we have hereunto subscribed our names.

CYRUS ROBERTS.
JOHN A. THROP.
